[57] CLAIM

The ornamental design for a saddle rack, substantially as shown and described.

DESCRIPTION

FIG. 1 is an isometric view of a saddle rack showing my new design;

FIG. 2 is a front elevational view thereof;

FIG. 3 is a rear elevational view thereof;

FIG. 4 is a top plan view thereof; and

FIG. 5 is a right side elevational view thereof, the left side being a mirror image of the right side shown.

Fig.1.

Fig.2.

Fig.3.

Fig. 4.

Fig. 5.
